UNITED STATES PATENT OFFICE

2,440,165

DEBRIS COLLECTOR FOR DRAINS

William Behrend, Milwaukee, Wis.

Application July 20, 1945, Serial No. 606,104

3 Claims. (Cl. 4—190)

1

My invention relates to improvements in debris collectors for drains.

The primary object of my invention is to provide means for equipping the fixed spiders in the drain outlets of ordinary wash bowls with a removable debris collecting spider which will not obstruct or impede the drainage from the wash bowl and will prevent the accumulation of debris on the fixed spider in a manner to impede such drainage.

A further object is to provide a debris collector for the outlet fittings of washbowls and similar receptacles which can be loosely mounted in such fittings and which has a grasping handle accessible from the upper end of the fitting, and by means of which the debris collector can be freely removed, cleaned and replaced whenever debris collects thereon.

A further object is to provide a drain pipe fitting having an ordinary permanently mounted debris collecting spider therein with an auxiliary removable spider-like member providing no additional obstruction to the flow of water through the fitting, and upon which the debris may collect and be removed with said member instead of being allowed to collect on the fixed cross bars of said permanently mounted spider.

A still further object is to provide a drain fitting with a removable spider-like debris collecting member having radially projecting arms of arcuate cross section, corresponding in transverse diameter to those of ordinary fixed debris collecting spiders, said member having a centrally disposed upwardly projecting grasping stem extending into proximity to the upper end of the fitting, whereby said member may be readily removed and replaced.

In the drawings:

Figure 1 is a vertical sectional view of a washbowl provided with an ordinary drain pipe fitting, and showing my improved removable debris collecting attachment mounted in such fitting.

Figure 2 is a perspective view of my improved debris collector as it appears when removed.

Figure 3 is a vertical sectional view of a modified form of outlet fitting with a modification of my improved debris collector applied thereto.

Like parts are identified by the same reference characters throughout the several views.

The washbowl 10 may be assumed to be representative of any liquid container provided with an outlet 11, removable valve 12, and a permanently fixed debris collecting spider having radially extending arms 13 and 14. Mounted upon the arms 13 and 14, I have provided a removable

spider-like member having arms 13' and 14' which are adapted to engage the fixed spider arms in superposed relation. For such engagement the arms 13' and 14' are preferably made crescent shaped in cross section, with arcuate under surfaces adapted to substantially fit the bars or arms 13 and 14, respectively. The arms 13', 14' of the removable member are of substantially the same horizontal diameter as the arms or bars 13 and 14, whereby their presence offers no increased obstruction to the flow of liquid through the fitting.

The outer end portions 16 of the arms 13' and 14' are preferably slightly upturned, and at the center of this removable member there is an upwardly extending stem 17 which serves as a grasping handle extending into proximity to the under surface of the valve 12. When the valve 12 is removed, the removable member may be freely lifted out by grasping the stem 17 and withdrawing the member vertically, the upturned portions 16 traveling in substantially scraping relation to the interior surfaces of the fitting.

In Figure 3, I have illustrated a slight modification, in which a fitting 11a is provided with an interior annular rib or annulus 20 in place of a permanently mounted debris collecting spider. The removable debris collecting member 21 has radially extending arms 22, preferably cylindrical in cross section, with extremities adapted to rest upon the rib 20 and provided with upwardly extending lip-like flanges 23 similar to the flanges 16 shown in Figures 1 and 2. This removable member is provided with a centrally disposed grasping stem 17a, substantially like the stem 17 shown in Figures 1 and 2.

I claim:

1. The combination with a drain outlet fitting provided with a stopper at its upper end and a fixed debris collecting spider downwardly spaced from the stopper, of a removable member interposed between the stopper and said fixed spider and having spider-like arms of arcuate cross section corresponding in number and substantially in horizontal diameter to those of the fixed spider, and adapted to register with those of the fixed spider and loosely rest thereon, whereby flow of water through the fitting will not be impeded by said removable member.
2. The combination with a drain outlet fitting provided with a fixed debris collecting spider, of a removable member having spider-like arms of arcuate cross section corresponding in number and horizontal diameter to those of the fixed spider and adapted to register with those of the

fixed spider and loosely rest thereon, the arms of the removable member having at their outer ends upturned lip-like flanges substantially in scraping proximity to the interior surfaces of the walls of the fitting, said removable member having spaces between its arms corresponding in size with those of the fixed spider.

3. The combination with a drain outlet fitting having a stopper at its upper end and downwardly spaced interior supports extending inwardly along radial lines with spaces between them for the passage of water through the fitting, of a removable debris collecting member having radially extending arms of substantially the same cross section as said supports and adapted to rest thereon, the spaces between said arms being substantially equal in diameter to the spaces between said supports, and the arms of the removable member being provided with upturned lip flanges at their outer extremities in substantially scraping proximity to the interior

surfaces of the fitting and their inner ends having a centrally disposed upwardly projecting stem adapted to serve as a grasping handle, with its upper end in close proximity to the under surface of said stopper.

5 WILLIAM BEHREND.
